UNITED STATES PATENT OFFICE.

JOSEPH FRANK, OF CHICAGO, ILLINOIS.

PIPE-BENDING MACHINE.

1,293,397.

Specification of Letters Patent.

Patented Feb. 4, 1919.

Application filed December 8, 1917. Serial No. 206,213.

To all whom it may concern:

Be it known that I, JOSEPH FRANK, a citizen of the United States, residing at Chicago, in the county of Cook and State of Illinois, have invented new and useful Improvements in Pipe-Bending Machines, of which the following is a specification.

My invention is concerned with tube bending machines of the character used in forming the crooks in brass band instruments, and it is designed to produce a machine of the class described which shall be simpler in its construction and more efficient in its operation than similar machines which have heretofore been employed.

In another aspect, it is concerned with a machine of the class described which can be readily changed to adapt it for making crooks of different radii.

As such devices have been constructed prior to my invention, where a mandrel has been employed to coöperate with the interior of the tube and bend it around the curved form, it has been considered necessary to employ either a roller or a stationary friction surface which shall engage with the tube on the convex side of the curve, and thus squeeze the tube against the mandrel on both sides. I have found that this outside roller or stationary friction surface is not essential, and is in fact detrimental as it produces unnecessary deformation of the surface of the tube with which it engages, as well as uses up unnecessary power in squeezing the material of the tube between it and the mandrel, and furthermore it limits the form of the curve to the arc of a true circle. By my novel construction in which this roller or friction surface is omitted, I

secure a better product in the finished tube, operate the apparatus with less power, and as the mandrel can give a little toward its free end, I am enabled within certain limits to form a curve that is not the arc of a true circle. This same omission of the outside roller or friction surface enables me within certain limits to make curves of different radii by merely changing the size of the forms and the angle at which the clamping mechanism stands.

To illustrate my invention I annex hereto two sheets of drawings in which the same reference characters are used to designate

identical parts in all the figures and of which—

Figure 1 is a perspective view of the device;

Fig. 2 is a vertical section, on an enlarged scale as seen in section on line 2—2 of Fig. 4;

Fig. 3 is a top plan view of a part of the apparatus shown as adjusted for making a curve of the smallest radius illustrated; and

Fig. 4 is a similar view showing it adjusted in full lines for making a curve of the largest radius shown, while the dotted line adjustment shows it arranged for the curve of an intermediate radius.

For carrying out my invention in its simplest and preferred form, I employ a base plate 5, preferably formed of heavy metal and secured upon a work bench or supported in any desired manner. Projecting upward from and rigidly secured to this base plate is the bearing stud 6, which preferably has the reduced portion forming a shoulder 12 upon which is fulcrumed the operating lever 7, which is conveniently detachably secured in place by the nut 11 on the threaded upper end of the stud 6. The stud has loosely mounted thereon one of the circular forms 9, of which I may employ three for instance, as illustrated in Figs. 3 and 4 by the forms 9, 9^a and 9^b, which are progressive by decreasing diameters, as shown, to make tubes having correspondingly decreasing radii. Each of these forms 9 has in the periphery thereof an annular groove 10, semi-circular in cross-section, and of the proper dimensions to correspond with the cross-section of the particular side of the tube with which it is used.

To hold the tube being operated on, I employ clamping mechanism, preferably such as illustrated, which consists of a block 13 having a groove 14 in the face thereof adjacent to the form 9, which groove 14 is of the same shape and dimensions as the groove 10. Associated with the fixed clamping member 13 is a movable member 15, of the same general construction, but smaller, having formed in its adjacent surface the similar groove 16, and adapted to be forced toward the fixed clamping member 13 to grip the tube to be bent between the two blocks 13 and 15 by the eccentric stud 17 which is mounted to

rotate in the base 5, as seen in Fig. 2, and which is moved by the arm 25 placed in the top thereof. To make the stationary clamping block 13 adjustable so that it can be used 5 with the forms 9, 9^a and 9^b of different diameter, as shown in Figs. 3 and 4, I provide it with a pair of vertical longitudinal slots 19 formed therein, through which slots extend upward the bolts 18 which have their 10 lower ends secured or fixed in the base 5, and by the employment of nuts on the upper ends of the bolts 18 I am able to place the block 13 in either one of the three positions shown in Figs. 3 and 4 and rigidly secure it 15 in either one of these positions.

The mandrel 20, which is a steel rod of the proper diameter to readily enter the tube to be bent with its outer end filling the tube, is supported in the horizontal plane 20 of the grooves 10, 14 and 16 by the arm 21 secured to the lever 7 and having its outer end 22 bent down at right angles and provided with an aperture through which the adjacent threaded end of the mandrel 20 25 is passed and secured rigidly in position by the nuts and lock nuts 23 and 23^a. A scallop 24 is formed in the arm 21 to permit the lever to be swung as far as is necessary to make a bend of 180 degrees in a tube without 30 its being interrupted by the arm 21 engaging the eccentric stud 17.

The operation of the device will now be readily apparent: With the parts in the position shown in Fig. 3, for instance, but 35 with the eccentric 17 turned to allow the movable block 15 to be moved away from the block 13, the tube to be bent is thrust between the grooves 14 and 16 and over the end of the mandrel 20 and shoved onto the 40 mandrel as far as necessary to make the length of curve contemplated. The eccentric 17 is then swung around to force the block 15 toward the block 13, thereby clamping the tube securely in position and the 45 lever 7 is then swung anti-clockwise with the result that the end of the mandrel 20 is drawn out of the tube, and as it is drawn out, it bends the portion of the tube which it is leaving around the form 9, leaving the 50 tube a perfect circle in cross-section while at the same time bending it into the shape of the form 9. The mandrel 20 can spring enough to accommodate it to the different sized forms 9, 9^a and 9^b which will be 55 changed as desired, and if a form employing a curve which is not a true circle should be employed the spring of the mandrel 20 will be sufficient to allow it to accommodate itself to the form of the curve and operate 60 just the same as if the form were curved on the arc of a true circle.

While I have shown and described my invention as embodied in the form which I at present consider best adapted to carry 65 out its purposes, it will be understood that

it is capable of modifications, and that I do not desire to be limited in the interpretation of the following claims except as may be necessitated by the state of the prior art.

What I claim as new and desire to secure 70 by Letters Patent in the United States is:

1. In a tube bending machine, the combination with a base adapted to have any one of a plurality of circular forms of different diameters secured on said base at the 75 same central point so as to produce curved tubes of different radii of curvature on the same machine, of one of said circular forms, an operating lever pivoted co-axially with the form, a single stationary clamping member 80 detached from the form and adjustable on the base to bring its tube engaging jaw with its axis tangential to the circular form irrespective of its diameter, means for securing the clamping member to the base in 85 any adjustment, a movable clamping member co-operating with the stationary clamping member to hold the tube, a mandrel supported at its outer end only by the lever so as to be free to spring and adapted to have 90 the free inner end enter a tube held in the clamping members and tangentially to the form, and means for holding the movable clamping member in position to co-operate with the stationary clamping member. 95

2. In a tube bending machine, the combination with a base, of a vertical bearing stud projecting upwardly therefrom adapted to have one of a plurality of annular forms of different external diameters but 100 having the same internal diameter fit snugly thereon and resting on the base so as to produce curved tubes of different radii of curvature on the same machine, one of said annular forms, an operating lever pivoted 105 on the stud, a single stationary clamping member detached from the form and adjustable on the base to bring its tube engaging jaw with its axis tangential to the form irrespective of its diameter, means for securing the clamping member to the base in any adjustment, a movable clamping member co-operating with the stationary clamping member to hold the tube, a mandrel supported at its outer end only by 110 the operating lever so as to be free to spring and adapted to have its free inner end enter a tube held in the clamping members and tangentially to the form, and means for holding the movable clamping member in 115 position to co-operate with the stationary clamping member. 120

3. In a tube bending machine, the combination with a base, of a vertical stud secured therein and projecting upward therefrom adapted to have one of a plurality of annular forms of different external diameters but having the same internal diameter fitted snugly thereon and rest on the base so as to produce curved tubes of different 125 130

radii of curvature on the same machine, one of said forms, an operating lever fulcrumed on the stud, a single stationary clamping member detached from the form and having two elongated slots therein extending substantially at right angles to the jaw thereof adjustable on the base to bring its tube engaging jaw with its axis tangential to the annular form irrespective of its diameter, bolts secured to the base extending through the slots in the form and provided with nuts, a movable clamping member coöperat-

ing with the stationary clamping member to hold the tube, a mandrel supported at its outer end only by the operating lever so as to be free to spring and adapted to have its free inner end enter a tube held by the clamping members and tangentially to the form, and an eccentric for holding the movable clamping member in position to coöperate with the stationary clamping member.

In testimony whereof I affix my signature.

JOSEPH FRANK.
